UNITED STATES PATENT OFFICE

100,202

DESIGN FOR A BICYCLE

John W. Clements, Richmond, Ind., assignor to
The Huffman Manufacturing Company, Dayton,
Ohio, a corporation of Ohio

Application April 1, 1936, Serial No. 61,888

Term of patent 14 years

To all whom it may concern:

Be it known that I, John W. Clements, a citizen of the United States of America, residing at Richmond, in the county of Wayne, and State of Indiana, have invented a new, original, and ornamental Design for a Bicycle, of which the following is a specification, reference being had to the accompanying drawing, forming a part thereof.

In the drawing,

Fig. 1 is a perspective view of a bicycle showing my new design; and

Fig. 2 is a top plan view thereof.

As illustrated in the design shown in the drawing, the dominant feature of the design consists

in the arrangement of the upper bar and the truss bar one above the other at the top of the frame and sweeping backwardly and downwardly from the head bar, the rear portion of each bar dividing and diverging in its backward sweep from the seat post mast, the several parts forming a continuous streamline curve from the head bar to the rear of the frame. The other features are fashioned to accentuate this streamlined arrangement.

I claim:

The ornamental design for a bicycle, substantially as shown and described.

JOHN W. CLEMENTS.
